UNITED STATES PATENT OFFICE.

JOHN E. MUHLEFELD, OF SCARSDALE, AND VIRGINIUS Z. CARACRISTI, OF BRONXVILLE, NEW YORK.

LOCOMOTIVE.

Application filed April 17, 1920. Serial No. 374,721.

To all whom it may concern:

Be it known that we, JOHN E. MUHLEFELD, mechanical engineer, a citizen of the United States, and resident of Scarsdale, in the 5 county of Westchester and State of New York, and VIRGINIUS Z. CARACRISTI, mechanical engineer, a citizen of the United States, and resident of Bronxville, in the county of Westchester and State of New 10 York, have invented certain new and useful Improvements in Locomotives, of which the following is a description.

This invention relates to steam motive power, and generically considered comprehends a railroad locomotive of either the simple, compound, triplex or other steam type having an improved boiler structure and a main and supplementary drive means upon which the boiler structure is balanced, 20 and whereby the adhesive pressure upon the rails may be utilized to full advantage in overcoming inertia and accelerating the starting motion of the locomotive and having improved means for utilizing waste heat.

It is one of the important objects of our present invention to provide a rigid and safe boiler structure consisting of a combination of water and fire tubes and a plurality of water circulating drums and a 25 steam generating cylinder, through which the gases of combustion pass, with spaced heads rigidly uniting the drums and the cylinder. Means of this improved boiler structure we aim to increase rigidity and thereby 30 obviate vibration to a large extent and relieve the parts of undue strains and stresses which have a tendency to promote rupture and leakage.

It is also an object of our invention to 40 provide means for the use of gaseous, liquid, pulverized or solid fuels, supplied either by manual or mechanical means, on grates or in retorts, or in suspension, in order to more effectively utilize the heat of combustion at 45 the furnace end of the boiler.

It is also an object of our invention to provide means in the nature of a fuel economizer for utilizing the waste gases for the purpose of heating the boiler feed water, 50 and for this purpose we have provided a novel arrangement of dampers controlling the passage of the products of combustion

through the smoke box of the locomotive whereby such products will be first directed into contact with the superheater units and then caused to impinge upon the walls of the 55 feed water reservoir both when the locomotive is in operation or is not using steam.

Our invention also contemplates an improved exterior arrangement of the steam delivery pipe connection between the superheater and the boiler header constituting the steam collecting dome, together with a steam separator and a throttle valve interposed in 60 said pipe connection.

In addition to the above mentioned features, we also provide an auxiliary superheater arranged in the locomotive cab or other suitable location for the purpose of supplying either saturated or superheated steam for the operation of the reversing 65 gear, air pump, grate mechanism, feed water pump, lubricator and other mechanical accessories with which the locomotive may be equipped, and which are now operated by 70 saturated steam.

With the above and other objects in view the invention consists in the improved construction, combination and relative arrangement of the several parts, as will hereinafter be more fully described, illustrated in the accompanying drawings, and incorporated in 75 the subjoined claims.

In the drawings, wherein we have illustrated one practical embodiment of our invention, and in which similar reference characters designate corresponding parts throughout the several views:

Figure 1 is a side elevation of a locomotive diagrammatically illustrating the salient features of our invention.

Figure 2 is a longitudinal section through the locomotive boiler, certain parts being broken away.

Figure 3 is a transverse section taken on the line 3-3 of Figure 1.

Figure 4 is a fragmentary section taken on the line 4-4 of Figure 3.

Figure 5 is a transverse section taken on the line 5-5 of Figure 1.

Figure 6 is a similar section taken on the 100 line 6-6 of Figure 1.

Figure 7 is a vertical sectional view through the smoke box of the locomotive,

showing one of the feed water reservoirs arranged therein, and illustrating the arrangement of the draught dampers when the locomotive is in operation.

5. Figure 8 is a similar view showing the arrangement of the dampers when the locomotive is not in operation.

Figures 9 and 10 are sectional and plan views respectively of a part of the supplemental drive unit.

10. Figure 11 is a detailed sectional view illustrating the manner of connecting the dry steam pipe to the intermediate boiler header which serves as a steam receiving and 15 storage dome.

15. Referring in detail to the drawings, wherein we have illustrated a locomotive which may be either of the simple, compound, triplex or other type, the locomotive 20 structure is mounted and supported in proper balance upon the main drive trucks 5 and the front and rear trucks 6 and 7 respectively. As is well known, in the customary locomotive construction the wheels of 25 the latter trucks exert no positive tractive effort upon the rails as an aid in the propulsion of the locomotive, but constitute merely auxiliary guiding and supporting means. However, that portion of the weight of the 30 locomotive which devolves upon the wheels of the rear truck 7 results in a high adhesive pressure of these wheels upon the track rails. As will be hereinafter more fully disclosed, it is one of the primary purposes of our 35 present invention to provide means whereby such adhesive pressure of these rear trailer wheels 7 may be utilized as a material supplement to the main tractive driving force of the wheels 5 upon the rails, whereby inertia may be quickly overcome and the starting movement of the locomotive accelerated. Similar supplemental drive means may also be applied to the leading truck 40 wheels of the locomotive.

45. The locomotive boiler, as herein shown, includes a pair of laterally spaced upper drums 8 which extend substantially the entire length of the boiler structure, and a pair of laterally spaced relatively short lower drums 9. The latter drums extend rearwardly of the cylinder or shell 10. A header 11 is secured upon the upper portion of the cylinder 10, which is in communication with said header through the openings 50 12 in the cylinder wall. The forward ends of the drums 8 are supported in said header and communicate therewith through the openings 13, the header walls having steam-tight connection with the wall of the drum.

55. The intermediate header 14 connects the rear end of the cylinder 10 with the upper and lower pairs of drums 8 and 9, and these drums communicate with the header 14 through the openings 15 and 16 respectively.

60. The drums 8 and 9 are connected to each

other at their rear ends by means of a third header 17, said drums communicating with the header through the openings 18 and 19, respectively.

65. The lower drums 9 extend through the fire box at either side of the grate 20, said fire box having refractory or other suitable side walls 21 covered by the insulating material or lagging 22.

70. Banks of vertically disposed water tubes 23 extend between and connect the upper and lower drums 8 and 9 at each side of the fire box to each other. These tube banks extend between the header 17 and the rear end of the cylinder 10.

75. A series of water circulating conduits 24 extend longitudinally through the fire box and are inclined rearwardly and downwardly from the rear header 17 to the intermediate header 14. Between the front ends of said conduits and the grate 20 a bridge wall 25 is built and a baffle wall 26 is arranged upon the upper sides of the conduits 24, and extends from the bridge wall 25 to a point adjacent the header 17. This baffle 80 wall at its side edges is adjacent to the banks of tubes 23. It will thus be apparent from reference to Figure 4 of the drawings that the greater volume of the products of combustion gases can only escape from the combustion chamber in a lateral direction, by passing between and in contact with the tubes 23. The flame and gases are in this manner drawn by induction through the tube banks, and then forwardly through the fire tubes 27 which extend longitudinally through the cylinder 10. These tubes at their rear ends are fixed in the rear wall of the header 14, and have their forward ends fixed in the front cylinder head 28.

85. An arch wall 29 spans the space between the drums 8 and immediately below this wall additional water tubes 30 are arranged and connect the headers 14 and 17 to each other. Through the header 17 spaced flues 31 are 90 disposed, and fixed at their ends to the header walls. Each of the tubes receives an auxiliary superheater unit 32, which furnishes superheated steam for the operation of the air pump and other mechanical 95 accessories of the locomotive. The saturated and superheated steam headers of the auxiliary superheater unit are arranged in the engineer's cab 33 or other suitable location and equipped with conveniently located 100 control valves.

105. The primary superheater indicated at 34 is arranged in advance of the cylinder 10 and the usual superheater units are provided and extend into the front ends of the 110 fire tubes 27. The saturated steam header is connected by the steam delivery pipe 35 to the upper and central portion of the intermediate header 14, which serves in the capacity of a steam dome. Any approved means 115

may be employed for establishing a steam-tight connection between the pipe 35 and the header. As seen in Figure 11 of the drawings, for this purpose we provide the wall 5 of the header 14 with a flanged nipple 36, with which the flanged end of the pipe 35 is engaged. Collars 37 and 38 are respectively engaged on the pipe 35 and nipple 36, and are connected by the clamping screws 39. 10 By this means the abutting flanges may be securely clamped in tight engagement with each other.

14^a indicates an indentation of the rear wall of header 14 opposite the steam delivery 15 pipe opening in order to properly stay this portion of the wall against internal steam pressure.

The superheated steam header is connected in the usual manner by a pipe 40 to each of 20 the steam chests. A throttle valve 41 is interposed in the pipe 35 and operated by suitable connections from the engineer's cab 33. The steam separator 41' may be located rearwardly of the throttle valve, or in advance 25 of the same as shown. It is to be observed that this pipe connection and the throttle valve are disposed exteriorly of the boiler proper and between the two upper drums 8.

In order to further contribute to the free 30 circulation of the water and steam between the cylinder 10 and the drums 8, said cylinder is connected to the drums by means of a plurality of curved alternately arranged pipes 42, said series of connecting pipes extending the entire length of the cylinder.

Between the bridge wall 25 and the cylinder 10, doors 43 are provided, as seen in Figure 5, which afford access to the interior of the boiler for the purpose of making 40 repairs and inspecting and cleaning the fire tubes 27. These openings and doors may be arranged in any other suitable manner.

The locomotive is provided at its front end with a smoke box 44, having the stack outlet 45. In the upper part of the smoke box and above the flues 27 a feed water tank or reservoir 46 is arranged. Preferably, one of these reservoirs is located at each side of the stack 45. A vertical plate or diaphragm 47 separates the smoke box from a chamber 48 into which the primary superheater headers and units are located. A main damper plate 49 is pivotally mounted at its lower end, as at 50, and is movable between the upper edge of the diaphragm 47 and a stop flange 51. At its lower end the diaphragm is provided with an opening 52 and a second pivotally mounted damper plate 53, controls the passage of the products of combustion through this opening. The damper plates 49 and 53 are connected to each other by a rod 54, and manual or automatic operating means of any suitable character is provided, whereby said damper plates may be operated in unison. Each of

the reservoirs 46 is preferably of cylindrical form, and is provided with a plurality of open ended tubes 46' extending longitudinally therethrough, and through which the products of combustion may freely pass. 70

In Figure 7 of the drawings we have illustrated the arrangement of the damper plates when the locomotive is in operation. From reference to said figure it will be seen that the damper plate 49 is in contact at its upper end with the upper edge of the diaphragm 47, while the damper plate 53 is in an open position. Thus the induced draught created by the steam nozzle draws the main products of combustion upwardly into contact 80 with the superheater units, which extend into the forward ends of the tubes 27, and hence through the tubes 46' of feed water heater.

A horizontally disposed plate 70 surrounds 85 the lower end of the stack 45 and between the steam nozzle 71, the plate 70 and the vertical diaphragm 47 a sheet of heavy wire netting or perforated plate 72 is arranged, through which the products of combustion 90 are drawn after passing through the tubes 46'. Thus any cinders will impinge against and be broken up by the netting or by other equivalent means, be deposited in the smoke box, and not projected through the stack outlet. 95

When the locomotive is not being operated, or the steam used, the damper plates are disposed in the position shown in Figure 8, wherein the upper end of the plate 49 is engaged with the stop flange 51, thereby 100 stopping the flow of the gases through the superheater flues while the plate 53 is disposed in its closed position over the opening 52. The gases through the lower boiler tubes now take the course indicated by the arrows, and are drawn upwardly in advance of the plate 49, hence through the tubes 46' and around the reservoirs 46 and finally through the foraminous wall 72 out through the stack 45. Thus in either arrangement 105 of the damper plates it will be seen that the gases are caused to travel through the tubes 46' and to also contact with the body wall of the feed water reservoir 46, thus highly heating the water therein before it passes to the reservoir outlet for delivery into the boiler. In this manner considerable economy in the consumption of fuel may be realized, and heat, which has heretofore been wasted, is conserved and advantageously employed, both when the locomotive is, and is not, using steam. 110

It will be understood, of course, that when the damper plates are disposed, as seen in Figure 7, the products of combustion issuing from the lower fire tubes 27 will pass directly through the opening 52 and be exhausted through the stack 45. 115

In connection with the improved locomotive boiler structure above described, we have 120 130

devised simple and effective means for applying a positive driving force to the wheels of the rear trailer truck 7, and thereby utilize the adhesive pressure of the wheels upon the rails for facilitating the starting and accelerating movement of the locomotive. To this end the frame 55 is loosely mounted at spaced points upon the truck axle 56, and extends rearwardly therefrom. At its rear end said frame is swiveled upon the upper end of the post 57, which, in turn, is swiveled at its lower end in a fixed bearing 58. Preferably a spring 59 surrounds the post 57 between the frame 55 and the bearing 58, and serves to normally maintain the frame in a relatively rigid position.

Upon the axle 56 spaced cog gears 60 are fixed. Pinions 61 secured upon a shaft 62, mounted in the frame 55, have constant meshing engagement with the respective gears 60. A beveled gear 63 is also fixed upon the shaft 62, and meshes with a beveled pinion 64 upon the longitudinal shaft 65. This shaft is driven by means of a steam turbine indicated at 66, and suitable reducing gearing is interposed in the line of said shaft, as at 67. A clutch 68 is also provided for the purpose of interrupting transmission of power to the drive pinion 64. This clutch may be of any desired automatic type, so that when the locomotive has attained a predetermined speed at which the pinion 64 will be rotated through the gearing at a speed in excess of the speed of rotation of the driving shaft 65, the clutch will open. In practice the turbine 66 functions until a speed of 15 to 25 miles is attained, when it is thrown out of operation either automatically or by the manual operation of a suitable cut-off valve in the steam feed pipe 69, which supplies the turbine with superheated steam from the steam chest pipe connection 40.

From the above description it will be seen that we have devised a very novel locomotive boiler structure, the several units of which are so correlated and rigidly secured to each other as to practically eliminate relative vibration. Thus torsional strains or stresses tending to weaken or disrupt the joint connections between the parts of the water and steam circulating system will be obviated. The weight of the locomotive structure is so distributed and balanced between the main drivers 5, the front supporting truck 6 and the rear supplementary driver 7 that a considerable adhesive pressure is exerted by the latter upon the rails. Therefore, by the application of a positive driving force to the wheels 7, as herein disclosed, a very appreciable additional tractive power is obtained. In view of the fact that the boiler has a very high steam generating capacity, the power necessary for the operation of the supplementary drive wheels will not lessen or de-

tract from the power applied to the main drive wheels 5. It will be understood that the means above referred to for transmitting and controlling the power to the supplemental drive wheels 7 is merely suggestive, and various equivalent means might be substituted therefor, the present application broadly comprehending the application of power to the wheels of the rear trailer truck in combination with a locomotive boiler structure of the type referred to, which has adequate steam and superheat generating capacity to operate the same. This particular power unit for the truck wheels 7 will, however, be embodied in an independent application for patent, as will also the feed water reservoir and damper plate arrangement forming the fuel economizer, and the specific gas, water and steam circulating system of the boiler. Further, it is to be understood that while we have herein shown and described one practical and satisfactory embodiment of the several combination features of our improved locomotive, these features may nevertheless be exemplified in various other alternative structures, and we accordingly reserve the privilege of adopting all such legitimate changes as may be fairly embodied within the spirit and scope of the invention as claimed.

While this particular description relates to a boiler adapted for a locomotive, such boiler may also be used for other stationary or mobile purposes, as for example, for steamship or road or farm tractors.

What we claim is:

1. In a locomotive, main and supplementary drive units, a balanced boiler structure having an appreciable portion of its weight sustained by the supplementary drive unit, and power transmitting means for the supplementary drive unit located on the opposite side of one of the main drive units from the supplementary drive unit and having its weight imposed upon the main drive units and directly actuated by the steam supply of the locomotive boiler.

2. In a locomotive, main and supplementary drive units, a boiler structure mounted upon said drive units and means located substantially centrally of the main drive units and having its weight imposed upon the main drive units for directly converting steam power supplied by the boiler into mechanical energy for the operation of said supplementary drive unit.

3. In a locomotive, main and supplementary drive units, a balanced boiler structure supported upon said drive units and having primary and auxiliary steam superheaters and power transmitting means for said drive units directly actuated by steam from the primary superheater.

4. In a locomotive, a boiler structure, said boiler structure including a plurality of

- steam and water circulating drums, a steam generating cylinder, and spaced headers rigidly connecting said drums and cylinder to each other, primary and auxiliary steam 5 superheaters, main and supplementary drive units supporting the boiler structure, and power transmitting means for said drive units actuated by steam from the primary superheater.
- 10 5. In combination with a locomotive having a steam generating capacity in excess of that required for the operation of the main drivers and having a rear overhanging portion extending an appreciable distance beyond the main drivers, a supplementary drive unit sustaining the weight of the overhanging rear portion of the locomotive structure, and power transmitting means having its weight imposed upon the main 15 drivers for directly converting steam power supplied by the locomotive steam boiler into mechanical energy for the operation of said supplementary drive unit.
- 15 6. In a locomotive, a boiler structure having upper and lower longitudinal drums, a fire tube cylinder, spaced headers rigidly connecting the drums and fire tube cylinder to each other, main and supplementary drivers upon which the weight of the boiler 20 structure is supported, and power transmitting mechanism for the supplementary drivers having its weight imposed upon the main drivers.
- 20 7. In a locomotive, a boiler structure having upper longitudinal drums extending approximately the entire length of the boiler, and lower longitudinal drums, a fire tube cylinder, spaced headers rigidly connecting the drums and fire tube cylinder to each other, main and supplementary drivers upon 25 which the weight of the boiler structure is supported, and power transmitting mechanism for the supplementary drivers having its weight imposed upon the main drivers. 40
- 25 8. In a locomotive, main and supplementary drive units, a boiler structure mounted upon said drive units, and means located intermediate of the end members of the main drive units and having its weight imposed upon the main drivers for transmitting power from the boiler for operating said supplementary drive unit independently of, or in combination with the main drive unit. 45
- 30 9. In a locomotive, main and supplementary drive units, a boiler structure mounted upon said drive units, means for transmitting power from the boiler to the main drive unit, and additional controllable means located substantially centrally of the main drive units and having its weight imposed upon the main drivers for transmitting power from the boiler for operating the supplementary drive unit independently, or in combination with the main drive unit. 50
- 35 In testimony that we claim the foregoing as our invention, we have signed our names hereunder. 55
